(57) **CLAIM**

The ornamental design for a table with pockets, as shown and described.

DESCRIPTION

FIG. 1 is a perspective view of an inventive table with pockets showing my new design;

FIG. 2 is an elevated front view thereof, the elevated back view thereof being identical thereto;

FIG. 3 is a top plan view thereof;

FIG. 4 is an elevated left side view thereof, the elevated right side view thereof being identical thereto;

FIG. 5 is a bottom plan view thereof;

FIG. 6 is a perspective view of a second embodiment of the inventive table with pockets, the table being shown with five pockets;

FIG. 7 is an elevated front view thereof, the elevated back view thereof being identical thereto;

FIG. 8 is a top plan view thereof;

FIG. 9 is a elevated left side view thereof, the elevated right side view thereof being identical thereto;

FIG. 10 is a bottom plan view thereof;

FIG. 11 is a perspective view of a third embodiment of the table with pockets, the table being shown with circular pockets;

FIG. 12 is an elevated front view thereof, the elevated back view thereof being identical thereto;

FIG. 13 is a top plan view thereof;

FIG. 14 is an elevated left side view thereof, the elevated right side view thereof being identical thereto; and,

FIG. 15 is a bottom plan view thereof.
